S. G. BARNARD

FUEL FEED CONTROL SYSTEM

Filed Oct. 17, 1921

Inventor
SAMUEL G. BARNARD

By Attorney
Richard J. Cook

UNITED STATES PATENT OFFICE.

SAMUEL G. BARNARD, OF SEATTLE, WASHINGTON.

FUEL-FEED-CONTROL SYSTEM.

Application filed October 17, 1921. Serial No. 508,288.

To all whom it may concern:

Be it known that I, SAMUEL G. BARNARD, a citizen of the United States, and a resident of the city of Seattle, county of King, 5 State of Washington, have invented certain new and useful Improvements in Fuel-Feed-Control Systems, of which the following is a specification.

This invention relates to an improved system for supplying and controlling the flow of fuel to the cylinders of an automobile engine, or the like, and more particularly it relates to certain valve control mechanism that may be used independently of or 5 in connection with a well-known type of vacuum system, and by its use makes possible the elimination of the usual carburetor float mechanism.

It is the principal object of the invention 0 to overcome the undesirable results caused by the pumping action of the float within a carburetor during travel over rough, or uneven surfaces, which causes irregular operation of the engine, and to do this by the elimination of the float within the carburetor 5 and providing means whereby fuel is delivered directly, by a siphoning action, from the vacuum tank into the intake manifold of the engine.

Another object of the invention resides in the provision of a four-way valve mechanism 0 that can be readily adapted to a universally used vacuum system without materially altering the latter, and which is of such construction that it may be manipulated to control the engine.

Other objects of the invention reside in the details of construction and combination of parts whereby an effective and desirable 5 system is produced.

In accomplishing these and other objects of the invention, I have provided the improved details of construction, the preferred forms of which are illustrated in the 5 accompanying drawings, wherein—

Figure 1 is a diagrammatic illustration, showing in side elevation the parts of a vacuum feed system embodied by the present invention.

Figure 2 is a sectional view of the vacuum tank equipped with a valve and siphoning feed pipe, according to the present invention.

Figure 3 is an enlarged, sectional view of the valve in the position it assumes when the engine is running.

Figure 4 is a similar view of the valve in position for coasting.

Figure 5 is a plan view of the valve and its control or adjusting rod.

Referring more in detail to the several views of the drawings—

1 designates what may be the fuel, or gasoline storage tank of an automobile, 2 the intake manifold of the engine and 3 the storage tank of the vacuum supply system. This latter is of a well-known type, used for the purpose of delivering an uninterrupted supply of fuel from the tank 1 to the engine, with the point of delivery at a higher level 70 than the supply.

The tank 3 comprises an upper or vacuum chamber 4 and a lower, or gravity feed tank 5. The chamber 4 has, at the top, an opening 6 into which a supply conduit 7 from the tank 1 extends, and also openings 8 and 9 which are connected, through valve mechanism presently described, with the intake manifold 2, and an air vent pipe 10. The feed tank 5 has, at the top, an air outlet channel 11 leading into the channel 9, also a lateral opening through which a siphoning conduit 13 extends into the tank nearly to the base thereof, and which leads to a carburetor connection 12 of the manifold 2 85 where it is equipped with a spray nozzle of any suitable type, as indicated at 14.

Mounted upon the tank 3 is a four-way valve 15 equipped with a plug 16 provided with a channel 17 whereby adjacent openings of the housing may be connected. A side opening 18 of the valve body connects with the air vent pipe 10, the top opening 20 leads to atmosphere, the bottom opening 21 has connection, by means of a pipe 22, 95 with the top opening 9 in the vacuum tank and the other side opening 23 leads into a vertical channel 24 in the valve body which, at the upper end, is connected by a tube 25 with the manifold 2 and at its lower end is connected by a pipe 26 with the vacuum chamber opening 8.

In a preferred construction, the valve plug is connected with an actuating rod, as shown at 28, in Figures 1 and 5, which extends 105 through the dash board 29 of the vehicle and is equipped with a handle 30 whereby it may be manipulated to move the plug to its different positions.

Within the chamber 4 of the tank 3, is a float 35. A lever 36 overlies the float and is connected at its ends to the float and a fixed

member 37. Another lever 38 is pivotally and centrally supported from the top of the tank and has connection at one end by means of a link 39, with the lever 36 and, at its opposite end, has valves 40 and 41 connected thereto that are movable to close and open the ports 8 and 9.

The bottom of the chamber 4 has an outlet 45 equipped with a valve flapper 46 which 10 opens automatically to permit a flow downwardly therethrough.

Assuming that the vacuum feed system is so constructed and is connected with the fuel supply tank and manifold of the engine, and 15 is equipped with a control valve 15 as described, the operation of the system would be as follows:

By turning the valve plug to the position as it is shown in Figure 3, it will be seen that 20 the chamber 5 normally has communication with the atmosphere through the ports 11 and 27, the valve channel 17 and pipe 10. Should there be no gasoline in either of the chambers, the float 35, by means of the levers 25 36 and 38, closes the valve 41 which admits air into the vacuum chamber and at the same time opens the valve 40 connected with the suction pipe 25. On cranking or otherwise starting the engine, a vacuum is then created 30 within the upper chamber which closes the flapper 46 in the lower part of the tank 4, thereby making the upper chamber air-tight, and causes the gasoline to be drawn from the main gasoline tank into the vacuum 35 chamber. As the gasoline enters the upper chamber the float rises and through connecting levers the valve 40 is closed and the valve 41 opened, which permits air to enter the vacuum chamber 5 through the air 40 vent 10. Air entering the lower chamber causes the valve flapper 46 to open and permits the gasoline in the upper tank to flow into the lower tank by gravity, thereby causing the float to lower as the gasoline flows 45 out. As the float lowers, the operation of the levers is again brought into action and the valve 40 is again opened and valve 41 closed, causing the filling action to be repeated, so that a supply of gasoline is always maintained 50 within the tank 5.

It is then apparent that with port 8 closed operation of the engine which causes a vacuum to be created within the manifold 2 will start a siphoning action through the 55 conduit 13 and the fuel will be sprayed into the manifold by means of the nozzle 14. It will be stated here that the carburetor 12 may be equipped with an auxiliary air opening and a valve as is usually provided in 60 carburetors, so that the mixture of fuel may be controlled.

When it is desired to shut off fuel from the engine for coasting or stopping, the valve plug is first given a quarter turn, so that its 65 channel 17 connects the opening 23 and 21,

as is shown in dotted lines in Figure 4. This causes the vacuum pressure within the manifold to be opened through pipe 25 and valve 15 into the chamber 5 and a reversal of flow through the tube 13 which drains the same 70 into the chamber 5 results. The valve is then advanced another one-fourth turn to the position as shown in Figure 4, which opens the suction to the atmosphere. This is the position that the valve assumes when 75 the engine is coasting.

It is apparent that this system of fuel feeding is also well adapted to motorcycle fuel tanks. In that case, the siphoning pipe 13 would lead from the fuel tank to the 80 spray nozzle as in the present case, and the opening 23 of the valve housing would be connected directly by pipe 25 with the manifold of the engine. The valve plug could then be manipulated so that the vacuum or 85 suction within the manifold could be used to cause the siphoning action of the fuel during running or to cause the pipe 13 to be drained back into the storage tank.

I claim:

1. In a fuel supply system of the character described, in combination, a fuel storage tank, a suction manifold, a siphon conduit leading from the tank into the manifold, a valve mounted on the tank having one side 95 open to atmosphere and having connections respectively with the suction manifold and with the storage tank, and operable to provide communication between the tank and atmosphere, or between the tank and the suction manifold, or between the suction manifold and atmosphere.

2. In combination with a fuel storage tank, a suction manifold and a vacuum feed tank, the latter comprising a vacuum chamber and a storage chamber and having a supply conduit leading into the vacuum chamber from the storage tank and having valved openings at the top into the vacuum tank having two adjacent openings communicating with atmosphere and having one of its other openings communicating both with the air inlet to the vacuum chamber and with the suction manifold, and its remaining opening communicating with the storage 110 chamber opening, a channeled plug for the valve operable to provide communication between the suction manifold and the storage chamber, the suction manifold and atmosphere or atmosphere and the storage chamber.

Signed at Seattle, Washington, this 11th day of October, 1921.

SAMUEL G. BARNARD.
